US0D1034346S

(12) **United States Design Patent** (10) **Patent No.:** **US D1,034,346 S**
(45) **Date of Patent:** **** Jul. 9, 2024**

(54) **RADIATOR GRILLE FOR VEHICLE**

(71) Applicant: **VOLKSWAGEN AKTIENGESELLSCHAFT, Wolfsburg (DE)**

(72) Inventor: **Tibor Juhasz, Wolfsburg (DE)**

(73) Assignee: **VOLKSWAGEN AKTIENGESELLSCHAFT, Wolfsburg (DE)**

(**) Term: **15 Years**

(21) Appl. No.: **29/883,494**

(22) Filed: **Jan. 30, 2023**

(30) **Foreign Application Priority Data**

Oct. 19, 2022 (WO) WIPO123831
